US0D1045662S

(12) United States Design Patent (10) Patent No.: US D1,045,662 S
(45) Date of Patent: * Oct. 8, 2024

(54) BUCKLE

(71) Applicant: ROGER VIVIER S.p.A., Sant'Elpidio a Mare (IT)

(72) Inventors: Diego Della Valle, Sant'Elpidio a Mare (IT); Romina Crini, Reggello (IT)

() Term: 15 Years

(21) Appl. No.: 35/517,196

(22) Filed: May 13, 2022

(80) Hague Agreement Data

Int. Filing Date: May 13, 2022

Int. Reg. No.: DM/220848

Int. Reg. Date: May 13, 2022

Int. Reg. Pub. Date: May 19, 2023

(30) Foreign Application Priority Data

Nov. 29, 2021 (EM) 008780472-0006
